UNITED STATES PATENT OFFICE.

HIRAM E. BARBER, OF SHERIDAN, WYOMING.

NAILING-STRIP.

1,358,922.

Specification of Letters Patent. Patented Nov. 16, 1920.

Application filed April 15, 1919. Serial No. 290,166.

To all whom it may concern:

Be it known that I, HIRAM E. BARBER, a citizen of the United States, residing at Sheridan, in the county of Sheridan, State 5 of Wyoming, have invented a new and useful Nailing-Strip; and I do hereby declare the following to be a full, clear, and exact description of the invention, such as will enable others skilled in the art to which it 10 appertains to make and use the same.

The present invention relates to a nailing strip, and has for its object to provide a device of this character which embodies novel features of construction whereby it 15 can be stamped from a sheet metal blank without waste and will provide an effective means for securing roofing sheets or the like in position.

Further objects of the invention are to 20 provide a nailing strip which can be readily driven in position and will become securely anchored upon the wood or other material so that there is no danger of the strip being accidentally pulled from position, and which will extend over the edges 25 of the roofing material or the like so that it will be held down and prevented from being blown up and torn by the wind.

With these and other objects in view, the 30 invention consists in certain novel combinations and arrangements of the parts as will more fully appear as the description proceeds, the novel features thereof being pointed out in the appended claims.

35 For a full understanding of the invention, reference is to be had to the following description and accompanying drawings, in which:—

Figure 1 is a top plan view of a portion 40 of a nailing strip which is constructed in accordance with the invention, a second nailing strip being indicated by dotted lines and arranged to show the manner in which successive nailing strips can be cut 45 from a blank of sheet material without waste.

Fig. 2 is a side elevation of the nailing strip.

Fig. 3 is a transverse sectional view on 50 the line 3—3 of Fig. 1, showing the manner in which the prongs or points are alternately deflected in opposite directions when driven into position.

Fig. 4 is a plan view of a slightly modified form of nailing strip. 55

Fig. 5 is a transverse sectional view on the line 5—5 of Fig. 4.

Fig. 6 is a transverse sectional view on the line 6—6 of Fig. 5.

Fig. 7 is a detail view of a modified form 60 of prong or driving point.

Corresponding and like parts are referred to in the following description and indicated in all the views of the drawings by the same reference characters. 65

The nailing strip which is designated by the reference character A is formed from sheet metal and is shaped with alternately arranged restricted neck portions 1 and wide portions 2, said neck portions and wide 70 portions being equi-distantly spaced and having a corresponding and symmetrical formation so that the wide portion of one strip will fit in the restricted portion of another strip at one side thereof. In Fig. 75 1 a second strip is indicated by dotted lines and this figure shows the manner in which the large portions of one strip fit against the restricted neck portions of another strip, thereby enabling these nailing strips to be 80 stamped or cut from a sheet metal blank without any waste. This enables the nailing strips to be economically manufactured and handled without loss. A driving point or prong 4 is stamped from each wide portion 85 of the strip and deflected downwardly, and these driving points are crimped or bent longitudinally in such a manner as to straighten and reinforce the same so that they can be readily driven into a wooden 90 roof or floor without danger of buckling or collapsing during the driving operation.

As indicated most clearly by Fig. 6, these 95 prongs 4 may be transversely bent so as to have an angle iron or V-shaped cross-section, thereby stiffening them so that they can be readily driven into position. Alternate prongs 4 have the pointed ends thereof beveled in opposite directions, as indicated at 5. This will cause alternate prongs or 100 driving points to be deflected laterally in opposite directions as they are driven into the wood, as indicated by Fig. 3, with the result that the driving points will securely anchor the strip to the roof or floor so that 105 there will be no danger of the strip being

accidentally pulled or removed from position.

A slight modification is shown by Fig. 4, in which portions of the strip between the 5 prongs or driving points 4 are bent or arched transversely, as indicated at 6. This is indicated more clearly by Fig. 5 which is a sectional view. This stiffens and reinforces the portions of the nailing strip between the prongs so that these intermediate portions of the strip will hold the roofing sheet or the like firmly in position and will not bend or bulge upwardly. The strip can, however, be readily bent or flexed at 10 the flat portions thereof between the arched portions 6, thereby enabling the strip to be handled and applied to a roof, floor or the like without difficulty.

A further modification is illustrated by 20 Fig. 7, in which the prong or driving point 4^a is shown as having opposite longitudinal edges thereof returned at 7 to stiffen and reinforce the same.

In order to accomplish this result, the 25 upper ends of the folded longitudinal edges 7 of the driving points are severed or cut away from the body of the strip as indicated at 7^a. It will be obvious that there are many different manners in which the sheet 30 metal prongs can be longitudinally bent or crimped to stiffen and reinforce the same, and when the driving points are thus reinforced it may be possible to use a lighter weight sheet metal stock in manufacturing 35 the nailing strips. This may result in a very appreciable economy. It will also be understood that there are many other variations and modifications of the invention which are within the scope of the claims, 40 and that the invention is not in any manner

restricted to the specific embodiments thereof which have been illustrated and described in this application.

Having thus described the invention, what I claim as new and desire to secure 45 by Letters Patent, is:—

1. A nailing strip formed of sheet metal and having a series of driving points stamped therefrom at intervals and bent downwardly, alternate driving points having the pointed ends thereof beveled in opposite directions so that they will be deflected laterally in opposite directions as they are driven in position. 50

2. A nailing strip formed of a continuous 55 narrow length of sheet metal which has a series of driving points stamped therefrom at intervals and bent downwardly, said driving points each having a longitudinally extending stiffening and reinforcing bend 60 therein.

3. A nailing strip formed of a continuous narrow length of sheet metal and having alternately restricted neck portions and wide portions, the wide portions of the strip 65 having driving points struck therefrom and bent downwardly and the portions of the strip between the driving points being transversely arched to reinforce and stiffen the same, said driving points being each 70 formed with a longitudinally extending stiffening and reinforcing fold.

In testimony whereof I have signed my name to this specification in the presence of two subscribing witnesses.

HIRAM E. BARBER.
